Primary Examiner — Elizabeth Albert(74) *Attorney, Agent, or Firm* — Design IP(57) **CLAIM**

The ornamental design for a roll file, as shown and described.

DESCRIPTION

FIG. 1 is a front perspective view of a first embodiment of a roll file showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front perspective view of a second embodiment of a roll file showing my new design;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

The broken lines in FIGS. 1 through 14 that define the bounds of the claimed design form no part thereof.

1 Claim, 8 Drawing Sheets(56)
